R. H. PRATT.

WALL PAPER.

No. 17,673.

Patented Aug. 30, 1887.

UNITED STATES PATENT OFFICE.

ROBERT H. PRATT, OF NEW YORK, N. Y.

DESIGN FOR WALL-PAPER.

SPECIFICATION forming part of Design No. 17,673, dated August 30, 1887.

Application filed July 5, 1887. Serial No. 243,473. Term of patent 3½ years.

To all whom it may concern:

Be it known that I, ROBERT H. PRATT, a citizen of the United States, residing at New York, in the county of New York and State of New York, have invented a certain new and original Design for Wall-Paper; and I do declare the following to be a full, clear, and exact description of the invention, such as will enable others skilled in the art to which it applies to make and use the same, reference being had to the accompanying drawing, and to the letters and figures of reference marked thereon, which form a part of this specification.

The invention relates to a certain new and original design for wall-papers, the same being conventional in style and of the embroidery or brocaded description, and will be hereinafter particularly described and claimed, reference being had to the accompanying drawing, forming a part hereof, and in which is represented a many-pointed star, B, on opposite sides of which occur the three-leaved or triangular-shaped figures C, on another side the clusters or diamond-shaped figures D, and on a fourth side the circular figure E. Between the figures C and E and the many-pointed star occur the leaves F, while below the clusters D occurs the urn or fountain shaped figure G. The urn-shaped figure has at its base a lattice or checker-board work, a. Between the diamond-shaped and the triangular-shaped figures C and D occur the flowers H and scroll-leaf figure I, a similarly scrolled shaped figure, I, occurring on opposite sides of the circular figure E, and at the ends of these scroll-leaved figures is the lattice-work or checker-board K.

The design may have a cross, b, of copper color, in the circular center c of the many-pointed-star figure, and in the spaces between

the arms of the cross may be smaller crosses, d, of a gold color. It may also have the spaces e of a light color, and golden lines f lying therein. There may also be radiating lines g in the circular figure E, which lines may be 45 of gold and copper colors.

The three-leaved triangular-shaped figures may have the links h and the circles i formed therein, the former preferably of gold color and the circles of copper color. 50

The cluster or diamond-shaped figures may have lines, j, of gold in the spaces between the several figures of the cluster, and the border or edges of all the figures may be of a darker shade than the parts inside of the same. It will also be observed that the lattice or checker-board work is preferably of copper color. 55

The design has been described with considerable particularity, but only for fullness and clearness, without so far limiting the design as not to cover substantially the same and colorable imitations thereof. 60

It may be added that small parallel lines may extend across the ground not covered by the figures or design proper—such lines, for instance, as lines j, previously referred to. 65

Having described the invention, what I claim is—

The design for wall-papers, consisting of the many-pointed star, the three-leaf or triangular-shaped figure, the cluster or diamond-shaped figure, the leaves and flowers, and the checker-board or lattice work, all substantially as shown and described. 70

In testimony whereof I affix my signature in presence of two witnesses. 75

ROBERT H. PRATT.
